JAR

Ira J. McCullough, Huntington Park, Calif., assignor to James A. Kammerdiner, Los Angeles, Calif.

Application December 7, 1931, Serial No. 579,381
Renewed August 14, 1933

15 Claims. (Cl. 255—27)

This invention relates to a well tool and relates more particularly to a jarring tool for use in fishing operations, etc. A general object of the present invention is to provide a practical, effective, adjustable jarring tool useful in fishing operations for imparting a jarring action to the fish or lost part in a well.

An object of this invention is to provide a jarring tool that is operable to effect a very heavy jarring action.

An important object of the invention is to provide a jarring tool that is adjustable from the surface of the ground to provide or impart jarring blows of different intensities. The jar provided by this invention is adjustable when in the well bore and in connection with the fish by simple manipulation of the operating string carrying the jar.

Another object of the invention is to provide a jarring tool of the character mentioned that is operable by simple reciprocation of the operating string. The tool is tripped or actuated to provide the jarring action by putting it under a tensile strain, and is reset by lowering or setting the operating string.

Another object of the invention is to provide a jarring tool that includes two sections related for limited relative longitudinal movement and an improved clutch or latch means for releasably holding the sections against relative longitudinal movement.

Another object of the invention is to provide a rotary well jar of the character mentioned in which the latch members release simultaneously and almost instantaneously upon the tool being subjected to a pre-determined strain so that there is very little friction and wear on the latch means.

Another object of the invention is to provide a jarring tool of the character described in which the working parts may be regulated or adjusted to release under various tensile strains through a novel mechanical adjusting means.

Another object of the invention is to provide a jarring tool of the character mentioned that does not interfere with the free circulation of fluid from the operating string.

A further object of the invention is to provide a jarring tool that is positive and dependable in operation and that may be easily and quickly reset for further actuation.

A further object of the invention is to provide a yielding control member for use in a jarring tool that yields but very slightly when subjected to very heavy compression strains.

Other objects and features of the invention, will be best and more fully understood from the following detailed description, during which description reference is had to the accompanying drawings, in which:

Fig. 1 is a side elevation of the tool provided by this invention showing it in an operating string of drill pipe carrying a fishing tool in engagement with a fish in a well bore. Fig. 2 is an enlarged longitudinal detailed sectional view of the upper portion of the tool showing the parts in the normal or unactuated position. Fig. 3 is an enlarged longitudinal detailed sectional view of the lower portion of the tool illustrating the parts in the unactuated positions. Fig. 4 is an enlarged longitudinal detailed sectional view of the central portion of the tool showing the releasable clutch means in the released position. Fig. 5 is an enlarged longitudinal detailed sectional view of the central portion of the tool showing the clutch members about to re-engage the teeth on the stem. Figs. 6, 7, 8, 9 and 10 are transverse detailed sectional views taken as indicated by lines 6—6, 7—7, 8—8, 9—9 and 10—10 on Fig. 2. Fig. 11 is a transverse detailed sectional view taken as indicated by line 11—11 on Fig. 3.

The tool provided by my present invention includes, generally, two body sections A and B connected for limited relative longitudinal movement, a mandrel or stem 10 slackly and yieldingly connected with the section A, clutch means 11 on the section B and the stem 10 for releasably holding the sections A and B against relative longitudinal movement, and means 12 for regulating or adjusting the means 11.

The sections A and B are the main or body parts of the tool and form a slackly linked or connected assembly adapted to be interposed in an operating string of drill pipe S as illustrated in Fig. 1 of the drawings. The sections A and B are connected for limited relative longitudinal movement and are telescoped one into the other. In the particular form of the invention illustrated in the drawings, the section A is the uppermost body section and is tubular, while the section B is the lower section and extends into the lower end of the section A. The upper section A is adapted to be connected with the lower end of the operating string S, while the section B is adapted to be connected with the fishing tool T for engaging the lost part or fish F. In the particular case illustrated in Fig. 1 of the drawings, the body section B is connected with the tool T through a length of drill pipe P and suitable connecting members.

The body section A is hollow or tubular and forms a housing for the principal portions of the tool. In the preferred construction, the section A includes an upper section or part 13, and a lower part 14. The upper part 13 is provided with a central longitudinal opening 15 and a screw threaded pin 16 at its lower end. The lower end portion of the opening 15 is of restricted diameter to provide an upwardly facing internal shoulder 17 in the body part 13. In accordance with the invention, the upper end of the body part 13 is connected with the operating string S through a rotatable and releasable connection. A top sub or connecting member 18 is rotatably and releasably attached to the upper end of the body part 13. In the particular case illustrated in the drawings, the member 18 is screw threaded into the upper end of the part 13. The threads connecting the part 13 and the member 18 are preferably right hand threads. A socket is provided in the upper end of the connecting member 18 to receive the threaded pin of a tool joint, or the like. A central longitudinal fluid passage or opening 20 is provided in the member 18. The lower body part 14 of the section A is screw threaded on the pin 16. The part 14 is a tubular member having a central longitudinal opening 21. A portion of reduced internal diameter is provided at the lower end of the body part 14 to provide an upwardly facing internal shoulder 22. The shoulder 22 is in the nature of a hammer face or jar shoulder for cooperating with a shoulder on the section B to provide the jarring blow when the means 11 is released.

The section B extends into and is slidably longitudinally in the opening 21 of the lower body part 14. A screw threaded pin 23 is provided on the projecting lower end of the section B to connect with a coupling 24 on the upper end of the portion of pipe P. A central longitudinal fluid passage 25 extends through the section B from one end to the other. In accordance with the invention, means is provided for holding the main sections A and B against relative rotation. In the particular case illustrated in the drawings, splines or keys 26 are provided on the section B to cooperate, with the key-ways 27 in the lower part 14 of the section A. A downwardly facing anvil shoulder 28 is provided on the section B. The shoulder 28 is spaced above the shoulder 22 when the means 11 is holding the sections A and B in the contracted position and is engaged or struck by the shoulder 22 when the means 11 is released. Packing 29 may be provided in an annular groove 30 in the section B to seal with the walls of the opening 21.

The stem 10 is slidably connected with the section A and is normally releasably connected with the section B by the clutch means 11. The stem 10 extends centrally through the upper section A and its upper end is slidable in the opening 20 of the member 18. Packing 31 is provided in a groove in the walls of the opening 20 to seal with the stem 10. The stem 10 is also slidable in the opening in the pin 16 and packing 32 is provided in the pin to seal with the stem. The stem 10 is tubular, having a central longitudinal opening 33 for passing circulation fluid from the connecting member 18 to the section B. In accordance with the invention, means is provided for holding the stem 10 against rotation relative to the connecting member 18. Pins 34 are threaded in diametrically opposite openings 35 in the member 18 and extend into longitudinal slots 36 in the upper end of the stem. Plugs 37 may close

the outer ends of the openings 35. The connection just described prevents turning of the stem 10 relative to the member 18 but permits limited relative longitudinal movement between the stem and the member 18.

The means 11 for releasably holding the sections A and B against relative longitudinal movement is operable to release the sections for relative movement upon a heavy tensile strain being put upon the tool through the operating string S. The means 11 includes a yielding member 38 yieldingly resisting upward movement of the section A relative to the stem 10 and clutch or latch members 39 on the section B, for cooperating with the stem 10 to releasably hold the stem against upward movement relative to the section B.

The yielding member 38 is arranged between the shoulder 17 of the section A and a nut 40 on the stem 10. The member 38 is adapted to yield or compress under a very heavy compression strain. In accordance with the invention, the member 38 is a single piece or body of hardened steel. The member 38 is tubular, surrounding the stem 10 and is corrugated or grooved so as to yield under compression. Longitudinally spaced annular grooves 41 are provided in the interior of the member 38 and a plurality of longitudinally spaced annular grooves 42 are provided in the exterior of the member. The grooves 41 are longitudinally staggered or offset with relation to the grooves 42 so that the member 38 is of corrugated cross section. When the clutch members 39 are in cooperation with the stem 10 and a heavy up-strain is put on the section A, the member 38 is compressed between the shoulder 17 and the nut 40. When the up-strain or tensile strain becomes sufficiently heavy, the member 38 yields or compresses slightly to permit upward movement of the section A relative to the stem 10 and section B.

The clutch members or latch members 39 are pivotally or tiltably connected to the section B and have releasable latching or clutching engagement with the stem 10. In the particular embodiment of the invention illustrated in the drawings, there are four like or identical latch members 39. The latch members 39 are arranged in the opening 21 and are tiltably connected with the upper end of the section B. A reduced head 44 having a downwardly facing annular shoulder 45 is provided on the upper end of the section B. The latch members 39 are arcuate in cross section to fit or engage about the head 44 and each member 39 has an upwardly facing shoulder 46 to cooperate with the shoulder 45. The cooperation of the shoulders 46 with the shoulder 45 positively holds the latch members 39 against longitudinal movement relative to the section B. The head 44 and the lower end portions of the latch members 39 are bevelled to permit tilting of the latch members 39 between the positions illustrated in Figs. 3 and 5 of the drawings.

Teeth 47 are provided on the interiors of the latch members 39 to cooperate with longitudinally spaced annular teeth 48 on the stem. The teeth 47 and 48 are adapted to cooperate to releasably hold the stem 10 and accordingly the section A against upward movement relative to the section B. The upper and lower faces of the teeth 48 are bevelled outwardly as illustrated throughout the drawings and the teeth 47 are shaped to effectively cooperate with the teeth 48. The upper faces of the teeth 48 and the lower

faces of the teeth 47 are but slightly tapered so that the teeth are effective in preventing longitudinal movement between the sections A and B when the latch members 39 are held in against the stem 10 in the manner hereinafter described. The several teeth 48 of the stem 10 are progressively narrower or shorter from the upper end of their series to the lower end of the series to compensate for pivotal movement of the latch members 39 so that all of the teeth 47 may be simultaneously disengaged from the teeth 48.

The invention includes means for normally holding the upper ends of the clutch members or latch members 39 in against the stem 10 so that the teeth 47 and 48 are in engagement. The means for holding the upper ends of the latch members 39 in against the stem 10 releases the members 39 for outward movement upon yielding of the member 38 and the resultant upward movement of the section A relative to the section B. A cage or sleeve 49 surrounds the stem 10 and is slidable in the upper end portion of the opening 21. The sleeve 49 is slidable on an enlargement 90 on the stem 10. The upper end of the enlargement 90 forms a shoulder 91 adapted to engage the lower end of the pin 16 to limit upward movement of the stem relative to the section A during actuation and resetting of the tool. The lower end of the sleeve 49 normally rests on an upwardly facing shoulder 50 on the walls of the opening 21 and is yieldingly held against the shoulder by a spring 51a. The spring 51a may be in the nature of a helical spring arranged under compression between the lower end of the pin 16 and the sleeve 49. An annular recess 51 is provided in the lower end of the sleeve 49 to receive the upper ends of the several latch members 39. The walls of the recess 51 are adapted to hold the latch members 39 in against the stem 10 so that the teeth 47 and 48 are maintained in cooperation.

Upon comparatively slight upward movement of the section A relative to the section B the sleeve 49 also moves upwardly so that the upper ends of the latch members 39 pass out of the recess 51. The cooperation of the bevelled teeth 47 and 48 causes the latch members 39 to move or pivot outwardly upon disengagement of the sleeve 49 from the upper ends of the latch members. It will be apparent that disengagement of the latch members 39 from the stem 10 permits upward movement of the section A relative to the section B so that the shoulder 22 is brought into jarring engagement with the shoulder 28. In practice, a very heavy tensile strain must be put on the sections A and B through the operating string S before the member 38 yields sufficiently to cause the sleeve 49 to move upwardly out of engagement with the latch members 39 so that the operating string S is stretched to a considerable extent. The heavy tensile strain together with the elasticity of the stretched or elongated operating spring S insures a very heavy upward jarring action when the shoulder 22 strikes the shoulder 28.

It is to be particularly noted that upon the sleeve 49 uncovering the upper ends of the latch members 39, the bevelled sides of the teeth 47 and 48 cooperate to cause the members 39 to suddenly and simultaneously move outward away from the stem 10. This sudden or instantaneous release of the means 11, puts a minimum of wear and friction on the latch members and the toothed portion of the stem 10.

75 It is a feature of the invention that the releas-

able holding means 11 may be reset or re-engaged when the tool is in the well bore. The lower end 53 of the sleeve 49 is bevelled downwardly and outwardly. After actuation of the tool the operating string may be lowered or permitted to settle to move the section A downwardly relative to the section B. Downward movement of the section A brings the lower end 53 of the sleeve 49 into camming engagement with the upper ends of the clutch members 39, 10 forcing the upper ends of the clutch members into the recess 51. Fig. 5 of the drawings illustrates the upper ends of the latch members in engagement with the lower end 53 of the sleeve 49. The spring 51a is operable to yield during such engagement of the upper ends of the members 39 with the sleeve 49 to permit the teeth 47 to move into proper engagement with the teeth 48 and allow the upper ends of the members 39 to pass into the recess 51 through their cooperation with the face 53. The spring 51a is also operable to return the sleeve 49 to its normal down position in engagement with the shoulder 50 after passage of the upper ends of the members 39 in the recess 51. Plugged openings 54 may be provided in the walls of the body part 14 through which suitable tools may be passed to move the sleeve 49 upwardly out of engagement with the latch members 39 if it is desired to manually trip the tool.

The means 12 is operable through manipulation of the operating string S to adjust or regulate the tool to trip when under tensile strains of different intensities. In accordance with the invention, the means 12 is in the nature of a 35 mechanical adjusting means that is operable upon turning of the connecting member 18 to cause the means 11 to release under different tensile strains. The means 12 includes a threaded connection between the nut 40 and the 40 stem 10. In practice the threads 55 connecting the nut 40 with the stem 10 have a comparatively heavy pitch and may be left hand threads. Diametrically opposite keys 56 are provided on the walls of the opening 15 to 45 cooperate with key-ways 57 in the nut to prevent rotation of the nut. It will be noted that the pins 34 connect the stem 10 and the member 18 against relative turning. The means 12 is such that turning of the connecting member 18 by manipulation of the operating string 50 threads the stem through the nut 40 and thus adjusts the stem longitudinally to adjust or regulate the releasable holding means 11. It is obvious that turning of the member 18 and the 55 stem 10 causes the threads 55 to shift the stem longitudinally in one direction or the other depending upon the direction of turning of the stem.

The mechanical adjusting means 12 includes a 60 lock or clutch member 58 arranged in the upper end of the opening 15. The clutch member 58 surrounds the stem 10 and has limited rotative movement relative to the section A. Diametrically opposite keys 59 are provided on the 65 clutch member 58 to cooperate with the keys 56. The keys 59 are spaced so that the clutch member 58 may turn through an arc of about 130°. Stop lugs 60 project upwardly from the upper end of the clutch member 58. There are two lugs 70 60 at diametrically opposite sides of the vertical axis of the member 58. The sides of the lugs 60 are vertical and radial. Similar diametrically spaced lugs 61 project downwardly from the lower end of the member 18 to cooperate with the 75

lugs 60. A spring 62 is arranged under compression between the nut 40 and the clutch member 58 to yieldingly hold the clutch member in an up position where its lugs 60 are adapted to cooperate with the lugs 61. The keys 56 terminate at points where they do not interfere with the turning movement of the lugs 61. The lugs 60 and 61 are positioned and related so that the connecting member 18 may be turned about 90° relative to the clutch member 58 and therefore relative to the section A, before and without causing turning of the clutch member 58. The connecting member 18 may be turned further together with the clutch member 58 which may be turned about 130°.

With the connection just described, it will be seen that the connecting member 18 may be turned the major portion of a revolution relative to the section A. The turning of the member 18 relative to the section A causes corresponding turning of the stem 10 so that the stem is threaded either up or down through the nut 40 depending upon the direction of turning of the member 18. Longitudinal adjustment of the stem 10 causes corresponding adjustment of the clutch members 39 relative to the section A and retaining sleeve 49. It will be seen that adjustment of the latch members 39 when in holding engagement with the stem 10 relative to the sleeve 49 permits the latch members to move out of the recess 51 upon the member 38 yielding under compression strains of different intensities. In this manner the tool may be regulated or adjusted to trip or operate under different pre-determined tensile strains. Openings 70 may be provided in the walls of the body part 13 to permit the lock member 58 to be moved downwardly by suitable tools to disengage its lugs 60 from the lugs 61. The pins 34 may be threaded out and disengaged from the slot 36 so that the member 18 may be turned without causing turning of the stem 10. When the pins 34 extend into the slot 36 the connecting member may be turned in one direction to adjust the stem 10. The pins 34 may then be disengaged from the slot and the member 18 turned in the other direction to return it to its original position where the pins may be re-engaged in the slot to provide for further adjustment of the stem and thus provide for a wide range of adjustment of the tool. In this manner the tool may be regulated or adjusted at the surface to operate under tensile strains within a given range and may again be adjusted when in the well bore to trip under a certain tensile strain within the chosen range.

It is believed that the operation of the tool provided by the present invention will be readily apparent from the foregoing detailed description. As just set forth, the tool may be adjusted to the surface to trip or operate under tensile strains within a known range. When the tool is in the well bore, the operating string S may be turned to cause corresponding turning of the connecting member 18 and stem 10. Due to the loose mounting of the lock member 58 and the relationship of the lugs 60 and 61, the connecting member 18 and stem 10 may be turned the major portion of a revolution in either direction. Turning of the stem 10 causes threading of the stem 10 longitudinally in the tool and corresponding relative movement between the sleeve 49 and the upper ends of the latch members 39. The sleeve 49 may in this manner be moved out of holding engagement with the clutch members 39 upon the sections A and B being subjected to

tensile strains of different strengths under which the member 38 yields different amounts. Upon disengagement of the sleeve 49 from the latch members 39 the latch members move outwardly permitting sudden upward movement of the stem 10 and section A bringing the shoulder 22 into hammering engagement with the shoulder 28. The tool may be quickly reset for operation by moving the section A downwardly relative to the section B to bring the sleeve 49 into holding engagement with the upper ends of the latch members 39.

It will be noted that the present invention provides a jarring tool that may be adjusted when in the well bore to provide jarring blows of different strengths or intensities. The adjusting means 12 is such that simple turning of the operating string S when not under tension, provides for the desired adjustment. The tool is simple and easy to operate and does not interfere with 20 nor depend for its actuation or adjustment upon the circulation of fluid through the operating string and fish.

Having described only a typical preferred form of my invention, I do not wish to limit myself 25 to the specific details set forth, but wish to reserve to myself any changes or variations that may appear to those skilled in the art or fall within the scope of the following claims:

Having described my invention, I claim:

1. A jarring tool for use in an operating string in a well including, two sections connected for limited relative longitudinal movement, means in one of the sections for releasably holding the sections against relative longitudinal movement operable to release the sections for relative movement upon a tensile strain being put on the sections, and means for adjusting the said means to release under different tensile strains including a member rotatably connected with said section and adapted to be attached to the operating string, a stem connected with the member for rotation therewith and to be slidably relative thereto, and a nut in said section through which the stem is threaded.

2. A jarring tool for use in an operating string in a well including, two sections connected for limited relative longitudinal movement, means in one of the sections for releasably holding the sections against relative longitudinal movement operable to release the sections for relative movement upon a tensile strain being put on the sections, and means for adjusting the said means to release under different tensile strains including a member rotatably connected with said section and adapted to be attached to the operating string, a stem associated with said means and connected with said member for rotation therewith and to be longitudinally movable relative thereto, a part in said section through which the stem is threaded, and means limiting rotation of the stem.

3. A jarring tool for use in an operating string in a well including, two sections connected for limited relative longitudinal movement, means in one of the sections for releasably holding the sections against relative longitudinal movement operable to release the sections for relative movement upon a tensile strain being put on the sections, and means for adjusting the said means to release under different tensile strains including a member rotatably connected with said section and adapted to be attached to the operating string, a stem associated with said means and connected with said member for rotation therewith and to

be longitudinally movable relative thereto, a part in said section through which the stem is threaded, a part having limited rotation relative to the section, and means limiting rotation of the said member relative to the last mentioned part.

4. A jarring tool including two sections related for limited relative longitudinal movement, a stem in one section, a yieldable member mounting the stem on said section, a clutch member carried by the other section for cooperating with the stem, and a part on the first mentioned section normally engaging the clutch member to hold the clutch member in cooperation with the stem and disengagable from the clutch member upon yielding of said member.

5. A jarring tool including, two sections related for limited relative longitudinal movement, a stem in one section, a yieldable member mounting the stem on said section, teeth on the stem, a toothed clutch member connected with the other section and adapted to cooperate with the teeth to hold the sections against relative longitudinal movement, and a part on the first-mentioned section normally engaging the clutch member to hold the clutch member in cooperation with the teeth on the stem and disengageable from the clutch member upon a predetermined yielding of said member.

6. A jarring tool including, two sections related for limited relative longitudinal movement, a stem in one section, a yieldable member mounting the stem on said section, a clutch member tiltably connected to the other section operable to cooperate with the stem to hold the sections against relative longitudinal movement, and a cage on the first mentioned section for holding the clutch member in cooperation with the stem and releasable from the clutch member upon a predetermined yielding of said member.

40 7. A jarring tool including, two sections related for limited relative longitudinal movement, a stem in one section, a yieldable member mounting the stem on said section, teeth on the stem, a clutch member for cooperation with the teeth to hold the sections against relative longitudinal movement, a cage on the said section for holding the clutch member in cooperation with the teeth and movable out of holding engagement with the clutch member upon a certain yielding of the yieldable member, and means for adjusting the stem longitudinally of the sections whereby the cage is releasable from the clutch member upon the yielding member yielding different extents.

55 8. A jarring tool including, two sections related for limited relative longitudinal movement, a stem in one section, a yieldable member mounting the stem on said section, teeth on the stem, a clutch member for cooperation with the teeth to hold the sections against relative longitudinal movement, a cage on the said section for holding the clutch member in cooperation with the teeth and movable out of holding engagement with the clutch member upon a certain yielding of the yieldable member, and means for adjusting the stem longitudinally of the sections whereby the cage is releasable from the clutch member upon the yielding member yielding different extents, including a nut threaded on the stem and mounting the stem on said section through the yielding member.

70 9. A jarring tool including, two sections related for limited relative longitudinal movement, a stem in one section, a yieldable member mounting the stem on said section, teeth on the stem, a clutch member for cooperation with the teeth

to hold the sections against relative longitudinal movement, a cage on the said section for holding the clutch member in cooperation with the teeth and movable out of holding engagement with the clutch member upon a certain yielding of the yieldable member, and means for adjusting the stem longitudinally of the sections whereby the cage is releasable from the clutch member upon the yielding member yielding different extents, including a nut threaded on the stem and mounting the stem on said section through the yielding member, and means for turning the stem.

10 10. A jar including, two sections related for limited relative longitudinal movement, means for releasably holding the sections against relative longitudinal movement, including a toothed stem yieldingly carried by one section, and a plurality of toothed latch members connected with the other section and cooperating with the stem, and a member carried by the first mentioned section normally holding the clutch members in cooperation with the stem and releasable from the stem upon the sections being subjected to a given tensile strain.

15 11. A jarring tool for use in connection with an operating string in a well bore including two sections related for limited relative longitudinal movement, means for releasably holding the sections against relative longitudinal movement including a part having an adjustable connection with one section and an element connected with the other section and adapted to have releasable holding cooperation with the said part, the part and element being disengageable upon a tensile strain being put on the sections, and a member directly connected to the operating string and operable upon manipulation of the operating string to adjust said adjustable connection whereby the said part and element may 40 disengage under various tensile strains.

20 12. In combination, an operating string to extend into a well, and a jarring tool connected to the operating string including two sections related for limited relative longitudinal movement, and means for holding the sections against relative longitudinal movement releasable upon a tensile strain being put on the sections, said means including a part having an adjustable 45 connection with one of the sections, the said means being releasable under different tensile strains upon adjustment of said part, a member operatively connected with said part to adjust said part upon being manipulated, and means directly connecting the member with the operating string so that said part is adjusted by manipulation of the operating string.

25 13. In combination, an operating string to extend into a well, and a jarring tool connected to the operating string including two sections related for limited relative longitudinal movement, and means for holding the sections against relative longitudinal movement releasable upon a tensile strain being put on the sections, said means including a part having an adjustable 60 connection with one of the sections, the said means being releasable under different tensile strains upon adjustment of said part, a member operatively connected with said part, means rotatably connecting the member with one of the sections, means for attaching the member to the operating string so that the member forms a connector between the operating string and the section and whereby said part may be adjusted by turning of the operating string.

14. A jarring tool for use in connection with an operating string in a well bore including two sections connected for limited relative longitudinal movement, means for rotatably connecting one of the sections with the operating string, means for holding the sections against relative longitudinal movement releasable upon a strain being put on the sections, and means actuated by turning of the operating string relative to said section to adjust the last mentioned means to release upon strains of different intensities being put on the sections.
15. Apparatus for jarring an object in a well including an operating string for extending into the well, two sections connected for limited relative longitudinal movement, means associated with one section for engaging the object in the well, means for connecting the other section with the operating string comprising a member attached to the operating string, and a rotatable connection between the member and the said other section, means for holding the sections against relative longitudinal movement releasable by a strain on the sections, and means for adjusting the last mentioned means governed by rotation of the operating string relative to said other section.
